LIQUID LEVEL CONTROL SYSTEM

Elvin E. Hollander, Bloomfield, N. J., assignor to
 Star Equipment Corporation, Bloomfield, N. J.,
 a corporation of New Jersey

Application April 30, 1938, Serial No. 205,278

2 Claims. (Cl. 137—106)

My invention relates to improvements in liquid-level control systems.

In many different cases, such as in the operation of washing or dry-cleaning machines, the maintenance of aquarium and swimming pools, and in the operation of industrial plants, there is the requirement that a solvent, water, chemical or other liquid, in a tank or some form of receptacle, be kept as fresh as possible and the level be substantially at a given level although it is being constantly supplied with fresh liquid at a rate which might vary over a substantial range, and in which the freshness of the liquid throughout the receptacle is maintained substantially more uniform than has been the case in the various systems and methods proposed heretofore.

Other objects and advantages will hereinafter appear.

For the purpose of illustrating my invention, 10 an embodiment thereof is shown in the drawing, in which

Figure 1 is a simplified, elevational view, partly in section, of a liquid-level control system constructed and operating in accordance with my 15 invention;

Figure 2 is an enlarged, fragmentary view taken from Figure 1, illustrative of the operating principle; and

Figure 3 is a view similar to Figure 1, showing 20 a modification.

The reference numeral 10 designates a tank or other receptacle for liquid. Means providing an inverted U-shape syphonic liquid-discharge passage from the tank comprises a relatively short 25 leg 11 communicating at its lower end 12 with the tank at the bottom thereof, and a relatively long leg 13 having its lower end 14 disposed below the lower end 12 of the short leg to make possible the syphonic action.

A passage 15 operates to vent the syphon from the interior of the tank at the level 16 at which it is desired the liquid be substantially maintained. The vent passage 15 is disposed to provide, with the long leg 13 of the syphonic liquid-discharge passage, an overflow-discharge from the tank at the level 16.

The long leg 13 of the syphon discharges into suitable treating apparatus represented at 17, and in which the liquid may be filtered, chemically 40 treated, or otherwise acted upon as might be required in any particular case, to restore the liquid substantially to the original condition it was in before having been fed to the tank 10.

The liquid is drawn from the apparatus 17 by a 45 suitable pump 18, and discharged into the tank 10, as shown.

In explaining the principle of operation, it will be assumed that the level of the liquid in tank 10 is momentarily at 16a, as represented in Figure 2.

With the foregoing in mind, it is one of the objects of my invention to provide an improved system of the character referred to in which the 50 level of the liquid in a receptacle is maintained

substantially at a given level although it is being constantly supplied with fresh liquid at a rate which might vary over a substantial range, and in which the freshness of the liquid throughout the receptacle is maintained substantially more uniform than has been the case in the various systems and methods proposed heretofore.

Other objects and advantages will hereinafter appear.

For the purpose of illustrating my invention, 10 an embodiment thereof is shown in the drawing, in which

Figure 1 is a simplified, elevational view, partly in section, of a liquid-level control system constructed and operating in accordance with my 15 invention;

Figure 2 is an enlarged, fragmentary view taken from Figure 1, illustrative of the operating principle; and

Figure 3 is a view similar to Figure 1, showing 20 a modification.

The reference numeral 10 designates a tank or other receptacle for liquid. Means providing an inverted U-shape syphonic liquid-discharge passage from the tank comprises a relatively short 25 leg 11 communicating at its lower end 12 with the tank at the bottom thereof, and a relatively long leg 13 having its lower end 14 disposed below the lower end 12 of the short leg to make possible the syphonic action.

A passage 15 operates to vent the syphon from the interior of the tank at the level 16 at which it is desired the liquid be substantially maintained. The vent passage 15 is disposed to provide, with the long leg 13 of the syphonic liquid-discharge passage, an overflow-discharge from the tank at the level 16.

The long leg 13 of the syphon discharges into suitable treating apparatus represented at 17, and in which the liquid may be filtered, chemically 40 treated, or otherwise acted upon as might be required in any particular case, to restore the liquid substantially to the original condition it was in before having been fed to the tank 10.

The liquid is drawn from the apparatus 17 by a 45 suitable pump 18, and discharged into the tank 10, as shown.

In explaining the principle of operation, it will be assumed that the level of the liquid in tank 10 is momentarily at 16a, as represented in Figure 2.

The condition which then exists may be expressed as follows:

$$Q_{13} = Q_{11} + Q_{15} + Q_a$$

wherein

5. Q_{13} is the rate of fluid-flow or discharge through the leg 13;
10. Q_{11} is the rate of liquid discharge upward through the leg 11 and over into the leg 13 due to the syphonic action, as represented by the arrows 19;
15. Q_{15} is the rate of overflow-discharge of the liquid from the tank through the vent passage 15 into the leg 13, as represented by the arrows 20; and
20. Q_a is the rate at which air is drawn or sucked into the vent passage 15 from the interior of the tank, between the edge 21 of the vent opening and the surface of the liquid at the level 16a, as represented by the arrow 22.

If Q_s at the time is less than $Q_{11} + Q_{15}$, the level 16a will drop to admit more air into the vent

25. passage 15 and increase Q_a and correspondingly decrease $Q_{11} + Q_{15}$ until the latter equals Q_s , at which time the liquid level will remain constant.

If Q_s at the time is greater than $Q_{11} + Q_{15}$, the level 16a will rise to admit less air into the vent

30. passage 15 and accordingly decrease Q_a and increase $Q_{11} + Q_{15}$ until the latter equals Q_s , at which time the liquid level will remain constant.

From the foregoing it will be seen that in my improved system, occurring variation of Q_s , even 35 over a substantial range, is automatically compensated for by the self-adjustment of the air-vent opening, whereby the level of the liquid is maintained at about the level 16.

Since there is withdrawal or discharge of the 40 liquid simultaneously from the top and bottom of the tank in my improved system, the freshness of the liquid throughout the tank is more uniform than would otherwise be the case.

In some cases it might be desirable to cause 45 discharge of liquid from tank 10 at a greater rate from one level than from another level, in which case the relation of the respective areas of the two discharge openings from the tank would be made to suit the particular condition 50 or requirement. For example, in an aquarium it might be more effective to discharge more water from the bottom of the tank, particularly if the inflow of fresh water is at the top. In such case, the diameter of the leg 11 would be made 55 greater than that of the vent passage 15.

In a practical embodiment of my invention, satisfactory results were obtained using a diameter of $\frac{1}{2}$ inch for the vent passage 15 and a diameter of $1\frac{1}{2}$ inches for each of the legs 11 60 and 13.

In my improved system, the vent passage 15 is disposed to be submerged at the desired level 65 16. Also, it is important in my improved system that the lower limit 9 of the crown portion 65 of the syphonic passage be disposed as shown to effect the syphonic action at the desired level 16, continuously and simultaneously with the overflow-discharge Q_{15} .

For the purpose of providing for an adjustment of the level maintained in the tank 10, an

arrangement such as is shown in Figure 3 might be used. In this case, there are the three vent passages 15a, 15b and 15c controlled by the valves 24, 25 and 26, respectively, and each corresponding to and serving the same purpose as the vent 5 passage 15 in Figures 1 and 2. It will be seen that with valves 24 and 26 closed and valve 25 open, as shown, the liquid level will be maintained at substantially 27, that with valves 24 and 25 closed and valve 26 open, the liquid level 10 will be maintained at substantially 28, and that with valves 25 and 26 closed and valve 24 open, the liquid level will be maintained at substantially 29. The principle of operation is the same as in Figures 1 and 2.

15

It will be understood that in any embodiment of my invention, the discharge from the leg 13 may go to waste, and the supply to the pump 18 taken from an independent source.

It will be understood that various modifications, other than those shown, are possible without departing from the spirit of my invention or the scope of the claims.

I claim as my invention:

1. In a liquid-level control system, a receptacle for liquid, and means providing an inverted U-shape syphonic liquid-discharge passage comprising a relatively short leg communicating at its lower end with said receptacle and a relatively long leg having its lower end disposed below the lower end of said short leg to make possible the syphonic action, said system being provided with a passage for venting the syphon from the interior of said receptacle at the level therein at which it is desired the 35 liquid be substantially maintained, said vent passage being disposed to be substantially entirely submerged at said level and to provide with said long leg of the syphonic liquid-discharge passage an overflow-discharge from said receptacle at said level, the lower limit of the crown portion of said syphonic passage being disposed substantially below said level and said crown portion of said syphonic passage being disposed to effect the syphonic action at said 40 level continuously and simultaneously with said overflow-discharge, the inlet side of said vent passage having a dimension in the vertical direction and being disposed to permit an overflow-discharge by way of said vent passage and 45 said syphonic liquid-discharge passage under conditions of liquid-level below the upper edge of said vent passage.

2. In a liquid-level control system, a receptacle for liquid, and adjustable means for syphoning off the liquid from said receptacle at selected levels; said means including means providing an inverted U-shape syphonic liquid-discharge passage comprising a relatively short leg communicating at its lower end with said receptacle and a relatively long leg having its lower end disposed below the lower end of said short leg to make possible the syphonic action, and a passage for venting the syphon from the interior of said receptacle at the level selected and 60 disposed to provide with the long leg of the syphon an overflow-discharge from said receptacle at the level selected.
